Primary Examiner — Samantha Q Lawrence(74) *Attorney, Agent, or Firm* — Aspire IP, LLC; Scott J. Hawranek(57) **CLAIM**

We claim the ornamental design for a liquid dispenser, substantially as shown and described.

DESCRIPTION

FIG. 1 is a perspective view of a liquid dispenser in a closed orientation in accordance with the present design;

FIG. 2 is a left side view of FIG. 1;

FIG. 3 is a right side view of FIG. 1;

FIG. 4 is a front view of FIG. 1;

FIG. 5 is a back view of FIG. 1;

FIG. 6 is a bottom view of FIG. 1;

FIG. 7 is a top view of FIG. 1;

FIG. 8 is a perspective view of a liquid dispenser in an open orientation in accordance with the present design;

FIG. 9 is a left side view of FIG. 8;

FIG. 10 is a right side view of FIG. 8;

FIG. 11 is a front view of FIG. 8;

FIG. 12 is a back view of FIG. 8;

FIG. 13 is a bottom view of FIG. 8; and,

FIG. 14 is a top view of FIG. 8.

The broken lines shown in FIGS. 1-4 and FIGS. 8-11 illustrate portions of the liquid dispenser that form no part of the claimed design.
